UNITED STATES PATENT OFFICE

2,178,703

FUEL BURNING APPARATUS

Charles W. Robbins, Cleveland Heights, Ohio, assignor to The Bryant Heater Company, Cleveland, Ohio, a corporation of Ohio

Application June 20, 1936, Serial No. 86,370

5 Claims. (Cl. 158—7)

This invention relates to gas burning apparatus and has particular reference to a conversion burner in the form of a unit which is adapted to be inserted through the door or lateral opening leading into the ash pit of a furnace or boiler initially designed for burning solid fuel.

The principal object of the present invention is to increase the amount of primary air which is supplied to the burner or burners and therefore to increase the efficiency and rating of the latter.

The above object is attained by the provision of features of construction and arrangement within the casing of the unit for controlling the flow of air passing lengthwise through the casing to supply the primary and secondary air needed for combustion, the arrangement being such as to so control the flow of air that a larger percentage is entrained with the gas passing to the main burner or burners than has heretofore been possible.

The invention may be briefly summarized as consisting in certain novel combinations and arrangements of parts which will be described in the specification and set forth in the appended claims.

In the accompanying sheet of drawings,

Fig. 1 is a vertical sectional view of a conversion unit constructed in accordance with my invention; and

Fig. 2 is a transverse sectional view substantially along the line 2—2 of Fig. 1.

Referring now to the drawing, the unit includes a casing 10 which is generally rectangular in shape, as indicated in Fig. 2, and is adapted to extend laterally and horizontally through the ash pit door where it will be supported and sealed in any desired manner. The structure of the furnace is indicated conventionally at 11. However, no attempt is being made to show the actual construction of the furnace wall or the method of sealing the unit in the opening thereof. The unit will be supported in operative position in any suitable manner, the front being shown in this instance supported by legs 12 while a suitable support will be placed under the inner end of the unit beneath the burner or burners.

The major portion of the unit extends inwardly beyond the wall 11 with a part projecting outwardly, and this part will have suitable provision for the admission of air which flows through the casing and is divided into primary and secondary air required for proper combustion. In this instance, the air is admitted to the casing 10 through a series of openings or slots in the form

of louvre openings 13 arranged at the front end of the unit which, since it is exposed, may be constructed and ornamented in any desired manner.

At 14 is shown the burner or burners, a burner or of the ring type being herein illustrated which may be in either one or two sections, but in this instance a two-section burner is illustrated. A mixture of gas and air is supplied to the burner by mixing tubes 15 one being shown in Fig. 1 and portions of both in Fig. 2. The main gas supply pipe is not shown but it leads to a suitable valve located at the outer part of the casing and here shown as a diaphragm valve 16 from which extends a delivery pipe 17 communicating with a manifold 18 shown in section in Fig. 1. Whether the pipe 17 leads to a manifold and thence to a plurality of mixing tubes or to a single mixing tube 15, is, however, immaterial.

As usual, the gas is delivered from the manifold to each mixing tube by a nozzle 19 so that the gas stream or jet will entrain the primary air therewith. As is customary, the orifice of the nozzle is controlled by a valve to vary the size of the gas jet and the velocity of the gas passing from the nozzle. In this instance the valve is adjusted by a rod 20 which is adapted to be turned and which extends forwardly beyond the furnace wall to a point for convenient adjustment, it being noted that the mixing of gas from the primary air and the admission of primary air to the mixing tubes 15 occur near the inner end of the casing 10 a distance inwardly from the front wall of the furnace.

Provision is made for shutting off or stopping the flow of air through the casing when the main valve 16 is closed and permitting the air to flow through the casing when the valve 16 is opened. This is accomplished by means of a door 22 hinged at its lower edge and extending crosswise of the casing so as to open and close an opening 23 which is located in the casing at or about the point where the latter extends through the furnace wall 11, this opening 23 and the air valve or door 22 being located above a fixed partition 24 which extends across the lower part of the casing just inwardly of the valve 16. When a gas valve of the diaphragm type is employed, the door is operated concurrently with the operation of the valve by a plunger or pressure responsive device 25 which may be connected to a diaphragm in a casing 26. The chamber above the diaphragm of the valve 16 may be connected by a pipe 27 to the chamber beneath the diaphragm in the casing 26 so that, when pressure

is supplied above the diaphragm of the gas valve 16, it will also be supplied beneath the diaphragm within the casing 26 so as to close the door, and when pressure is relieved above the diaphragm of the valve 16, it will be relieved beneath the diaphragm in the casing 26 and allow the door to open. In this instance, the plunger 25 engages a lever 28 which in turn engages the projection 29 on the door, as shown in Fig. 1. The lever 28 has a counterweight 30 which substantially balances the weight of the door 22. As these parts per se do not form a part of the present invention, further reference to them is unnecessary.

15 There also extends through the casing 10 a small tubular casing 31 which at its inner end has an upright extension 31a. The pipe for the pilot gas extends through the horizontal part of the casing 31 and supplies gas to the pilot 32 which is in igniting relation to the main burner 14 and stands just in front of the upright portion 31a of the casing 31. Projecting out through the top of the upright portion 31a of the casing 31 is a thermal element 33 which extends down 20 through the portion 31a of the casing 31 and has a control member extending through the casing 31 to a switch box indicated at 34 and containing switch elements utilized in connection with the control circuit for the valve 16 including the 25 coil of a solenoid control valve. These parts likewise form no part of the present invention and further description is deemed unnecessary.

Coming now to the features constituting the main part of the invention, it will be observed 30 that I provide immediately in front of the mixing tubes 15 a baffle 35 which extends across the lower part of the casing 10. Likewise, it will be observed that the mixers 36, which are located at the rear ends of the mixing tubes 15 and into 35 which the gas nozzles 19 extend, are provided with openings 37 of fairly large size for the primary air. These openings are located at the top of the mixers immediately above the baffle 35 and are in inclined position, the arrangement of the baffle and these openings being such that the air which passes inwardly through the casing 10 (primary air and secondary air) is required to pass over the baffle 35 and a part of it to sweep 40 over the primary air openings 37.

It will be observed also that associated with 50 each primary air opening 37 is a shutter 38 which is hinged at 39 and biased toward open position by a spring 40. The hinge 39 for the shutter is supported on the mixer of each burner tube at 55 the rear of the primary air opening 37 and the shutter extends forwardly and normally upwardly over the opening 37 in a manner such that the shutter 38 acts as a scoop or diverter to enhance the flow of primary air through the 60 openings 37 and into the mixers.

The position of each shutter may be adjusted by turning a rod 41 which extends horizontally from a point adjacent the baffle 35 forwardly to the front part of the casing 10 outside the furnace wall where it can be conveniently reached and turned when adjustment is desired. In this instance the forward end of the rod 41 engages a pin 42 which is mounted for endwise movement in the upper part of the mixer and at its forward end engages a downturned flange 43 of the shutter at the rear of the hinge pin 39. The rod 41 has a threaded connection with the manifold 18 so that when the rod 41 is turned in one direction it moves the pin 42 forwardly so as to move the shutter toward the primary air inlet opening 37.

and when the rod 41 is turned in the reverse direction, the action of the spring 40 is to open the shutter.

With this arrangement, the air which passes through the casing 10, i. e., both primary and secondary air, is all required to pass over the baffle 35 and part of the air sweeps over the inclined primary air inlet openings 37 which are so arranged that the air tends to sweep into these openings to augment the flow created by the suction effect of the gas jets. Furthermore, this action is augmented by the deflecting or scooping effect of the shutters 38. Thus by the velocity effect and by the deflector action of the shutters the primary air which enters the burner tubes is augmented, permitting an increase in the gas rate to a higher figure than would otherwise be possible without detriment to the flame characteristics, thus increasing the rating of the burner. Of course, the amount of primary air can be varied whenever desired by adjusting the shutters 38.

While I have shown one embodiment of the invention which operates very effectively, I do not desire to be confined to the details of arrangement or construction which have been illustrated but aim in my claims to cover all modifications which do not involve a departure from the spirit and scope of the invention in its broadest aspects.

Having thus described my invention, I claim:

1. In gas burning apparatus, a main burner, a duct adapted to extend through a lateral door of the furnace or the like and adapted to convey primary and secondary air to the burner, the burner having a mixing tube with an air inlet opening located in the casing, a baffle extending across the lower part of the casing so that the primary and secondary air is required to pass over the same, and a shutter above the baffle over the opening for the mixer.

2. In gas burning equipment, a burner, a duct for conveying primary and secondary air adapted to extend inwardly through a lateral opening in the wall of the furnace or the like and to project into the ash pit of the latter, a mixing tube connected with the burner and having a mixing end with an air inlet opening controlled by an adjustable shutter, and a baffle extending across the duct for diverting primary and secondary air and causing it to flow over the same and part of it toward the opening and its shutter.

3. In gas burning equipment, a burner, a conduit adapted to extend substantially horizontally into a furnace and having at or near its forward end an air inlet opening and at or near its inner end an outlet opening for the flow of secondary air to the burner, a burner tube connected to the burner and extending forwardly into the conduit and provided with a mixing chamber having a primary air opening, and a deflector adjacent said opening and in inclined relation with respect to the direction of air flow through the conduit whereby the amount of primary air supplied to the burner tube is augmented by the deflecting or scooping effect of the deflector.

4. In gas burning equipment, a burner, a conduit adapted to extend substantially horizontally into a furnace and having at or near its forward end an air inlet opening and at or near its inner end an outlet opening for the flow of secondary air to the burner, a burner tube connected to the burner and extending forwardly into the conduit and provided with a mixing chamber having a primary air opening which is inclined upwardly

5 and rearwardly with respect to the direction of air flow through the conduit whereby the amount of primary air admitted to the burner tube is augmented by the velocity effect of the air passing through the conduit, and a baffle extending crosswise of the conduit in front of said primary air opening.

10 5. In gas burning equipment, a burner, a conduit adapted to extend substantially horizontally into a furnace and having at or near its forward end an air inlet opening and at or near its inner end an outlet opening for the flow of secondary

air to the burner, a burner tube connected to the burner and extending forwardly into the conduit and provided with a mixing chamber having a primary air opening, a deflector adjacent said opening and in inclined relation with respect to the direction of air flow through the conduit whereby the amount of primary air supplied to the burner tube is augmented by the deflecting or scooping effect of the deflector, and a baffle extending across the conduit in front of said deflector. 10
